UNITED STATES PATENT OFFICE.

GEORGE WILSON SANBORN, OF LOWER GILMANTON, NEW HAMPSHIRE.

AUTOMATIC BRAKE.

SPECIFICATION forming part of Letters Patent No. 339,698, dated April 13, 1886.

Application filed February 15, 1886. Serial No. 191,937. (No model.)

To all whom it may concern:

Be it known that I, GEORGE WILSON SANBORN, a citizen of the United States, residing at Lower Gilman-ton, in the county of Belknap and State of New Hampshire, have invented 5 certain new and useful Improvements in Automatic Brakes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The special object of the invention is to automatically actuate the brakes of a wagon in going down hill by gravity and through the instrumentality of a rocking bolster, as hereinafter described.

20 Figure 1 of the drawings is a longitudinal vertical section of a wagon with the brakes applied; Fig. 2, a similar view with the brakes not applied; and Fig. 3 is a bottom view.

In the drawings, A represents the front and 25 B the rear axle of a freight-wagon wherein no reach or springs are employed, while the bottom is secured by a king-bolt to the front bolster and axle. I arrange on the bottom of the wagon-body the two parallel keepers c c, in 30 which is placed the fast block D, that is provided with a median hole, d. Through the latter passes the rod E, to whose rear end is pivoted the middle of the brake-bar F, while the other end extends forward between axle A 35 and bolster G, where it is held by a pin, a. The wagon-body has a short reciprocating movement with the keepers c c on the rod E, said movement being governed by the distance of the brake-shoes f f from the rear wheels of 40 the wagon when the latter is not on a declin-ing grade. The bolster G is slightly beveled or chamfered on the rear edge of the upper

side and on the front edge of the lower side, so that when going down hill the bolster may rock on the head of bolt a', and turn suffi- 45 ciently to put on the brakes, as shown in Fig. 1 of the drawings. By this construction and the use of the two bolts a a', I am enabled to give the desired vibratory motion to the rock-er-bolster G.

50 I am aware that the use of gravity to put on the brakes is not broadly new.

I am aware that an armed bar hinged to rear axle has been combined with a roller hav-ing arms connected with the brake-bar to op- 55 erate the latter; also, that four shouldered and inclined blocks on the bottom of wagon have been combined with friction-rollers on the bolsters of both front and rear axles; also, 60 that a roller trunnioned in keepers on the front axle has been combined with a brake bar sus-pended from body and jointed bars to actuate the brakes; but none of these combine the same instrumentalities for operating the brakes when going down hill; but 65

What I do claim as new, and desire to secure by Letters Patent, is—

1. The combination, with a front bolster, bevelled on the rear edge of the upper side and the front edge of the lower side, of the two 70 bolts a a', connecting said bolster with the body and front axle of a wagon, as and for the purpose specified.

2. The combination, in a wagon, of the 75 brake-bar F with the rod E, cross-block D, the keepers c c, and the rocking bolster G, as and for the purpose set forth.

In testimony whereof I affix my signature in presence of two witnesses.

GEORGE WILSON SANBORN.

Witnesses:

JOHN A. GOSS,
CLARA A. BATCHELDER.
